TIRE

William D. Alexis, Wadsworth, Ohio, assignor to The
B. F. Goodrich Company, New York, N.Y., a corpora-
tion of New York

Filed Mar. 2, 1966, Ser. No. 1,254

Term of patent 14 years

(Cl. D90—20)

FIG. 1 is an elevational view of a tire showing my new design, it being understood that the full line portion of the design is repeated throughout the circumference of the tread of the tire; and

FIG. 2 is an enlarged fragmentary sectional view taken substantially along the line 2—2 of FIG. 1.

The dominant features of my design reside in the full line portions of the drawing.

I claim:

The ornamental design for a tire, substantially as shown and described.
